UNITED STATES PATENT OFFICE.

JOHN G. REBER, OF CHICAGO, ILLINOIS, ASSIGNOR TO THE J. W. SEFTON MANUFACTURING COMPANY, OF SAME PLACE AND ANDERSON, INDIANA.

PAPER VESSEL.

SPECIFICATION forming part of Letters Patent No. 635,349, dated October 24, 1899.

Application filed November 21, 1898. Serial No. 697,090. (No model.)

To all whom it may concern:

Be it known that I, JOHN G. REBER, a citizen of the United States, residing at Chicago, in the county of Cook, in the State of Illinois, have invented a certain new and useful Improvement 5 in Paper Vessels, of which the following is a description, reference being had to the accompanying drawings, forming part of this specification.

10 My invention relates to paper pails or vessels such as are commonly used for carrying oysters, liquids, and semiliquids; and it consists in certain improvements whereby without any material increase in the cost a pail 15 may be produced having substantial advantages over those heretofore used, as will be hereinafter more fully explained.

In the accompanying drawings, Figure 1 is a plan view of the blank for my improved pail 20 properly cut and creased for folding into pail form; Fig. 2, a middle vertical section of the folded pail with its lid open; Fig. 3, a corresponding view with two of the lid-flaps bent down to horizontal position to close the pail, 25 and Fig. 4 a perspective view of the pail with the two remaining lid-flaps bent down upon the top of the two above mentioned and secured in such position by their coöperating fastening devices to completely close the pail.

30 The same letters of reference are used to indicate corresponding parts in the several views.

As shown in Fig. 1, the blank for my improved pail is composed of the bottom portion 35 A, sides B C D E, corner-folds F G H I, and top flaps or lid portions J K L M, all of which, with the exceptions hereinafter noted, are or may be substantially the same as heretofore common in pails of this class. The exceptions 40 are that each of the top flaps or lid portions J and L is provided upon its opposite edges with extensions O for a purpose hereinafter explained, while the other two top flaps K M differ from those heretofore employed in that each is suitably shaped to form 45 two portions K and K' and M and M', separated from each other by the creased lines a, which adapt the parts K' M' to be folded over and pressed flat upon the parts K and M, respectively. When the parts K' M' are so folded 50 over upon the parts K M, the outer ends or

points of the parts K' M' will project over upon the side walls C E of the pail, as shown in Fig. 2, for a purpose hereinafter explained.

The blank shown in Fig. 1 is folded into 55 open-pail form in the usual manner, the corner-folds F G being overlapped upon the outer face of the side C and the corner-folds H I overlapped upon the outer face of the side E and these corner-folds then secured to said 60 sides of the pail by means of the inserted and clenched ends of the wire bail N in the usual manner. The ends of the bail are not passed through the depending portions K' M' of the top flaps K M; but, on the contrary, the depending 65 lower ends or points of these flaps overlap and cover the inner clenched ends of the bail N upon the inner faces of the side walls C E of the pail, and thereby serve a twofold purpose. In the first place by covering the 70 inner ends of the bail and the apertures in the sides C E and corner-folds through which the bails pass they add somewhat to the liquid-tight character of the pail by rendering less liable leakage through the sides of the 75 pail around the ends of the bail; but their principal purpose and advantage are to cover the ends of the bail and prevent the latter from interfering with the "nesting" of the 80 open pails in quantities one within another 85 in accordance with the usual practice of storing and handling such pails. Heretofore the projecting inner ends of the bail, especially where not clenched down tightly upon the inner faces of the side walls of the pail, frequently 90 formed obstructions to this nesting of the pails not only in the act of nesting them, but also in the act of withdrawing them from the nest for use, the projecting inner ends of the bail in one pail frequently catching 95 upon the sides or outer portions of the bail of the pail inserted immediately within the first-mentioned pail, thus interfering with both the snug insertion and the ready withdrawal of the second pail and sometimes 100 damaging it if they are hastily or carelessly handled. By the provision of the depending extensions K' M' of the top flaps K M the inner ends of the bails are entirely covered and the interior of the pail caused to present a perfectly-smooth surface to the exterior of the pail inserted immediately within it, thus

facilitating the snug nesting of the pails and the ready withdrawal of them from the nest.

When the top flaps J L are bent downward to horizontal position, as in Fig. 3, their inturned side extensions O will contact with and bear against the side walls B D of the pail and serve to brace and support said top flaps from depression beyond normal closed position by any weight or force applied to the top of the pail. The parts O not only serve to support the closed cover of the pail, but by fitting snugly against the sides C E of the pail they render the pail more nearly slop-proof at the four corners of its top. I am not the first to employ these side extensions O upon the cover-flaps of a pail of this general character for the purpose of bracing and supporting the cover of the pail when closed and rendering it more nearly slop-proof at the four corners of its top; but these extensions O are peculiarly useful in my improved pail in combination with the cover-flaps K and M and the metal fastening devices with which the latter are provided, as will be now explained. The extensions O upon the cover-flaps J L are preferably of such shape that their edges b, Fig. 2, will, as the flaps J L are bent downward toward horizontal position, contact with the side walls B D of the pail slightly before the flaps J L reach true horizontal position and offer a yielding resistance to farther downward movement of said flaps and tend to spring them upward from horizontal position when pressure upon them is relieved, Fig. 3. Now the cover-flaps K M are provided with coöperating sheet-metal fastening devices P Q of well-known form, by means of which when said flaps are bent downward to horizontal position on top of the flaps J L they may be strained toward each other or drawn perfectly taut by means of the metal fasteners P Q and secured in such position by the reverse bending of the tongue of the fastener P in the usual manner, as seen in Fig. 4. By pressing the four flaps down firmly to or toward horizontal position at the time the fasteners P Q are engaged and then drawing the flaps K M strongly toward each other by means of the fastener P and bending the latter down upon itself the result will be that the parts O, which have been strongly pressed at their outer edges against the side walls B D, will tend to spring the cover-flaps J L upward slightly, which tendency will be resisted by the taut connection between the flaps K M holding the latter firmly in the position to which they were depressed at the time the fastening devices P Q were engaged and secured. The two cover-flaps J L will thus be pressed upward tightly against the two cover-flaps K M, with the result that a very snug and tight joint will be produced and maintained between the several members of the cover of the pail and the latter be thus very tightly and securely closed.

The double thickness of the cover-flaps K

K' and M M' affords a firm base for the secure attachment of the metal fasteners P Q, enabling such flaps to be drawn strongly toward each other by means of such fasteners, as above explained, without danger of tearing the fasteners loose from the flaps. It will be understood, however, that such double thickness of these cover-flaps is not absolutely essential to the feature of my invention last above described, since without departing from it the extensions K' M' might be omitted, or if retained for the purpose of affording a firm attachment for the metal fasteners they need not be of sufficient size to overlap the sides C E of the pail and serve the further purpose of covering the ends of the bail.

As will be apparent from Fig. 1, the blank of my improved pail is cut from the same square or rectangular blank heretofore required for the simplest and cheapest styles of pails of this general character, so that the advantages of my improved pail are attained without any increase in the cost of the pail, while as compared with pails of a somewhat different character heretofore made and intended to embody some of the advantages attained in my improved pail the latter is very much cheaper than such old pails, as well as very much more simple in construction.

Having thus fully described my invention, I claim—

1. A paper pail of the character described, having its two cover-flaps K M provided with the extensions K' M' folded inward upon the flaps K M and overlapping the side walls C E of the pail and covering the inner ends of the wire bail N, substantially as and for the purpose set forth.

2. The herein-described paper pail having its cover-flaps J L provided with the extensions O adapted when said flaps are bent downward to horizontal position to fit against the side walls C E of the pail to aid in tightly closing the pail and to contact at their edges with the side walls B D thereof to brace and support the cover of the pail, and having its other two cover-flaps K M provided with the coöperating fastening devices P Q for drawing them tightly together and holding the cover of the pail closed, substantially as and for the purpose set forth.

3. The herein-described paper pail having its cover-flaps J L provided with the extensions O adapted when said flaps are bent downward to horizontal position to fit against the side walls C E of the pail to aid in tightly closing the pail and to contact at their edges with the side walls B D thereof to brace and support the cover of the pail, and having its other two cover-flaps K M provided with extensions K' M' folded inward upon the flaps K M, said cover-flaps K K' and M M' being provided with coöperating fastening devices P Q for drawing them tightly together and holding the cover of the pail closed, substantially as and for the purpose set forth.

4. The herein-described paper pail having

its cover-flaps J L provided with the extensions O adapted when said flaps are bent downward to horizontal position to fit against the side walls C E of the pail and to contact at their edges with the side walls B D thereof to brace and support the cover of the pail, and having its other two cover-flaps K M provided with the extensions K' M' folded inward upon the flaps K M and overlapping the side walls C E of the pail and covering the inner ends of the wire bail N, said cover-flaps K K' and M M' being provided with coöperating fastening devices P Q for holding the cover of the pail closed, substantially as and for the purpose set forth.

5. The herein-described blank for a paper vessel, composed of the bottom A, four sides B C D E, corner-folds F G H I, and four cover-flaps J K L M, the flaps K M being provided 10 with the extensions K' M' adapted to be folded

inward upon the flaps K M and overlap the sides C E, substantially as and for the purpose set forth.

6. The herein-described blank for a paper vessel, composed of the bottom A, four sides B C D E, corner-folds F G H I and four cover-flaps J K L M, two of said flaps, J and L, being provided with the extensions O adapted in the closed pail to fit against the sides C E and contact at their edges with the sides B D, 15 and the other two of said flaps, K and M, being provided with the extensions K' M' adapted to be folded inward upon the flaps K M and overlap the sides C E, substantially as and for the purpose set forth.

JOHN G. REBER.
